EX

OR D 303

D-303

May 303

Job E. Owens, Jacob Ebert and
Elbridge G. Dyer of Hamilton Ohio.
Letters Patent No. 303. Dated July 22 1850.

~~~~~  
The Schedule referred to in these Letters Patent and making part of the same.

~~~~~  
To all whom it may concern:

Be it known that we, Job E. Owens,
Jacob Ebert and Elbridge G. Dyer, of Hamilton in the County of Butler and State of
Ohio, have invented or produced a new ornamental design for Cooking Stoves, and we do here-
by declare the following to be a full, clear and exact description thereof, reference being had to
the annexed drawings making part of this specification in which Fig. 1, is one of the side plates
of the elevated oven, containing a door (a) bordered with a scolloped moulding (b) and decorated

Dec. 30 3

2

at the centre of its panel with the figure of an eagle (a') and two cornucopias (a" a").

Fig. 2. is the front plate of the elevated oven which is decorated at its centre by a symmetrical ornament c. the half of which is shewn and its two side panels (d) are decorated with a running ornament, a member of which is shewn at (e). (m) is a fragment of a running ornament which borders its top and side edges.

Fig. 3. is one of the side plates of the stove, having two quadrangular panels (f, g.) the panel (f) being decorated at its centre with a symmetrical ornament (h) the half of which is shown, and the panel (g) having at its centre a circular bead (i) containing a rose and forget-me-nots (j); there is also on this plate a scroll (k) the half of which is shown, and also ornament (l).

The front plate of the stove is shown at Fig. 4; the two doors are similarly ornamented; (l) is the half of a symmetrical ornament which occurs at the centre of each door.

Fig. 5. is the sliding hearth.

Fig. 6. represents by sections the several mouldings referred to by like letters in the other figures.

Having thus fully and exactly described the ornaments of my stove, what I claim therein as new and desire to secure by Letters Patent is the combined ornamental design and configuration of plates for a Cooking Stove substantially as herein set forth and represented in the accompanying drawings.

In testimony whereof, we have hereunto set our hands before two subscribing witnesses.

Witnesses.
